DESIGN FOR A RADIOCABINET

Giovanno Lattarulo, Chicago, Ill., assignor of ten per cent to Frank Di Bellis and twenty-five per cent to Marcelene Lattarulo, both of Chicago, Ill.

Application June 26, 1933. Serial No. 48,535

Term of patent 3½ years

To all whom it may concern:

Be it known that I, GIOVANNO LATTARULO, a citizen of Italy, residing at Chicago, in the county of Cook and State of Illinois, have invented a new, original, and ornamental Design for a Radiocabinet, of which the following is a specification, reference being had to the accompanying drawing, forming part thereof.

Figure 1 is a view in front elevation of a radiocabinet, showing my new design.

Figure 2 is a top plan view thereof.

The sides and the back of the radiocabinet are understood to be substantially the same as the front, except for the front panel assembly.

I claim:—

The ornamental design for a radiocabinet as shown and described.

GIOVANNO LATTARULO.
